UNITED STATES PATENT OFFICE

ROBERT A. DORRILL, OF LITTLE SILVER, NEW JERSEY

GARMENT HANGER

Application filed August 13, 1931. Serial No. 556,749.

This invention relates to garment hangers and particularly hangers for supporting both garments having shouldered portions, such as coats, and garments such as trousers, skirts and the like. The invention is especially related to the garment hanger described and claimed in my copending application Serial No. 499,615, filed December 3, 1930, which consists of a main portion including suspending means and parts extending in opposite directions at opposite sides of the suspending means and in a common vertical plane when the hanger is suspended, said parts being shaped to receive the shoulders of a coat or the like, and an auxiliary portion connected to the ends of the shoulder receiving parts and including a trousers-supporting bar to receive trousers or the like, horizontally spaced from the plane of said main portion so that the edges of a coat or the like mounted on the shoulder receiving parts may be arranged between said main portion and said trousers-supporting bar.

One object of the present invention is to provide a garment hanger of this general character wherein the auxiliary trouser-supporting portion shall be pivotally mounted upon the main portion so that it may be arranged in positions with its plane perpendicular to the plane of said main portion or substantially parallel thereto, whereby all portions of the hanger may be disposed in close, parallel and compact relation for transportation of the hanger, as in baggage, and the auxiliary portion may be arranged in offset relation to the main portion when the hanger is in use to support a trousers or the like.

Another object is to provide such a hanger wherein the main portion and the auxiliary portion have cooperating means for positively holding the auxiliary portion in either of the above-mentioned positions.

Other objects are to provide a hanger of this character wherein the means for holding the auxiliary portion with its plane either perpendicular to the plane of the main portion or substantially parallel thereto, consists of cooperating projections and recesses on the main portion and the auxiliary portion, or consists of a hook pivotally mounted

on the main portion to separably engage the auxiliary portion; to provide a garment hanger of the general character described wherein the main portion has a tie-bar connecting the shoulder-receiving parts and the auxiliary portion has a sleeve pivotally mounted upon said tie-bar; to provide a garment hanger of the general character described wherein the auxiliary portion includes a bar pivotally mounted between the ends of the shoulder-receiving parts of the main portion; and to obtain other advantages and results as will be brought out by the following description.

Referring to the accompanying drawings in which corresponding and like parts are designated throughout the several views by the same reference characters:

Figure 1 is a front elevation of a garment hanger embodying my invention, showing the auxiliary trousers supporting portion in two of its positions.

Figure 2 is a fragmentary transverse vertical sectional view through the hanger shown in Figure 1 showing the auxiliary trousers supporting portion disposed with its plane perpendicular to the plane of the main portion.

Figure 3 is a fragmentary detailed perspective view of the means on the main portion for cooperating with the auxiliary portion to hold the latter in its various positions relative to the main portion.

Figure 4 is a view similar to Figure 1 showing a modified form of the invention.

Figure 5 is a view similar to Figure 2 of the construction shown in Figure 4.

Figure 6 is a top plan view of the construction shown in Figure 5.

Figure 7 is a front elevation of another form of the garment hanger.

Figure 8 is a fragmentary transverse vertical sectional view therethrough showing the auxiliary portion with its plane perpendicular to the plane of the main portion.

Figure 9 is a top plan view of the construction shown in Figure 8.

Figure 10 is a view similar to Figure 7 showing another form of the invention.

Figure 11 is a view similar to Figure 8 of the construction shown in Figure 10.

Figure 12 is a fragmentary top plan view of the construction shown in Figure 11.

5 Figure 13 is a front elevation of a garment hanger embodying a further modification of the invention. 70

Figure 14 is a transverse vertical sectional view therethrough showing the auxiliary 10 portion perpendicular to the plane of the main portion.

Figure 15 is a fragmentary sectional view on the line 15—15 of Figure 13.

Figure 16 is a view similar to Figure 13 15 showing another modification of the invention, and

Figures 17 and 18 are transverse vertical 20 sectional views through the hanger shown in Figure 16 respectively illustrating the auxiliary portion in positions substantially parallel to the plane of the main portion and perpendicular to the plane of the main portion.

Specifically describing the embodiment of 25 the invention illustrated in Figures 1 to 3 inclusive, the hanger comprises a main portion A formed of one piece of wire to receive the shoulders of a shouldered garment such as a coat, and an auxiliary portion B to receive garments such as trousers, skirts or the like. The main portion includes a suspending hook 1 at opposite sides of which and extending in opposite directions in the same plane are shoulder receiving parts 2 suitably 30 shaped to receive the shoulders of a coat or the like, said shoulder-receiving parts being connected by a tie bar 3 disposed in substantially the same plane with said shoulder-receiving parts. The auxiliary portion B 35 comprises the trouser-supporting bar 4 and supporting arms 5 that are disposed approximately parallel to the bar 4 and extend inwardly in spaced relation thereto. The extremities of the supporting arms 5 are shown 40 as connected to a sleeve 6 rotatably mounted on the tie bar 3.

With this construction, the auxiliary portion B may be arranged in positions with its plane approximately parallel to the plane of 50 the main portion as shown by solid lines and dot and dash lines in Figure 1 or with its plane approximately perpendicular to the plane of the main portion as shown in Figure 2. For holding the auxiliary portion in 55 all of these positions, the tie-bar 3 may be formed with polygonal protuberances 7 one at each end of the sleeve 6, and the sleeve may be formed with polygonal end portions 8 to slip over said protuberances upon relative longitudinal sliding movement of the tie bar and the sleeve 6.

When the hanger is suspended by the hook 1 the main portion is arranged in substantially a vertical plane, and when the auxiliary portion B is disposed perpendicularly to

the main portion, the trousers supporting bar 4 is offset from the shoulder-receiving parts 2 so that the front edges of a coat or the like may be arranged in the spaces between the supporting arms 5 and the main portion A. The trousers or the like may be applied to the bar 4 by slipping one end upwardly between the supporting arms 5 and the bar 4 and draping the garment over the bar. 75

With this construction, when a coat or the like is placed upon the main portion A and the trousers of the like are placed upon the trouser-supporting bar, the trousers are entirely exposed and fully accessible so that they can be removed from the hanger without hindrance by the coat and without disturbing the coat. Similarly, after the coat has been applied to the hanger the trousers may be easily applied to the supporting-bar without interference from the coat. 80

If the user desires, the auxiliary portion B may be disposed beneath the tie-bar 3 and substantially in the plane of the main portion A as shown by solid lines in Figure 1, and for conveniently packing the hanger the auxiliary portion may be arranged beside the main portion as shown by dot and dash lines. As above stated, the auxiliary portion may be positively held in any of these positions by cooperation of the protuberances 7 and the polygonal ends of the sleeve 6. 85

A modification of the invention is shown in Figures 4 to 6 inclusive, where the main portion A has a separate tie-bar 10, and the auxiliary portion B has a sleeve 11 rotatable on the tie-bar 10 to which the supporting arms 5 are connected. The tie-bar 10 has a projection 12 to cooperate with notches 13 in one end of the sleeve 11, for holding the auxiliary portion B in positions with its plane substantially parallel with or perpendicular to the plane of the main portion A. 100

A modification of the invention is shown in Figures 7 to 9 inclusive. Here 110 the main portion A is in general of the same construction as shown in Figure 1 of the drawings, the main difference being in the construction of the tie-bar 14. The auxiliary portion B differs from the corresponding portion of the construction shown in Figure 1 in that the end portions of the supporting arms 5 are bent to form eyes 15 for rotatably mounting the auxiliary portion on the tie-bar 14, and the extremities of said supporting arms are bent to form lateral projections 16, one of which cooperates with a protuberance 17 formed in the tie-bar 14 by crimping the latter. The other projection 16 on the auxiliary portion is shown as cooperating with shoulders 18 on a sleeve 19 secured upon the tie-bar. The operation of this form of the hanger is substantially the same as the operation of the forms hereinbefore described. 115

The form of the invention shown in Figures 10 to 12 inclusive is in general the same as that shown in Figures 7 to 9, the main difference being in the construction of the auxiliary portion B. In this form, the auxiliary portion comprises a plate 20 which has one edge bent to form a tubular portion or sleeve 21 which is cut away at its ends at 22 to form shoulders for cooperation with the protuberances 17 and the shoulders 18 on the tie-bar. The other edge of the plate has ears 23 which are bent over the end portions of the supporting arms 5 to secure said supporting arms to the plate.

15 A further modification of the invention is shown in Figures 13 to 15. Here the main portion C of the hanger includes two shoulder-receiving parts 24 one end of each of which is separably connected to one end of 20 the other. The separable connection is shown as consisting of a suspending hook 26 having a threaded shank passing through openings 27 in the overlapping ends of the parts 24, and threaded into a nut 28 at the side of 25 the parts 24 opposite the hook, whereby the parts are clamped together between the nut 28 and the hook. The other ends of the shoulder-receiving parts 24 are returned at 29 and provided with openings 30 in which are separably fitted the ends 31 of a tie-bar 32.

The auxiliary portion D is shown as comprising a trousers-supporting bar 33 to the ends of which are connected wire-supporting arms 47 which are also connected to a plate 48 having one edge portion rolled to form a tube 49 which is rotatably mounted on the tie bar 32. The manner of attaching the arms 47 to the plate 48 and mounting the plate 48 on the tie-bar is in general similar to the construction shown in Figure 10. For holding the auxiliary portion D in a plane perpendicular to the plane of the main portion C, one end of the tube 49 is provided with a notch 50 which cooperates with a projection 51 on the tie-bar 32. The notch 50 and projection 51 correspond to the notch 13 and projection 12 in the construction shown in Figure 4. The auxiliary portion D may if desired be held in a position parallel to the main portion as shown by dot and dash lines in Figure 13, by engagement of another notch 52 with the projection 51.

Figures 16 to 18 inclusive show a hanger embodying other features of the invention. 55 This form of the hanger includes a main portion E having two shoulder-receiving parts 34 one end of each of which is separably connected to one end of the other. As shown, this separable connection consists of the threaded shank 35 of a suspending hook 36 passing through the openings 37 in the ends of the shoulder-receiving parts and screwed into a plate 38 at the side of the parts 34 opposite the hook, whereby said parts are 60 clamped between the plate 38 and the hook.

The other ends of the shoulder-receiving parts 34 are turned inwardly toward each other in substantially axial alinement and shaped to form trunnions 39 upon which is rotatably mounted a bar 40 forming a part 70 of the auxiliary trouser-supporting portion F.

To this bar 40 are secured the extremities 75 41 of the supporting arms 42 for the trouser-supporting bar 43. A plate 46 is connected to the end portions of the supporting arms 42 in a manner similar to that in which the plate 30 is connected to the supporting arms 28 in the construction shown in Figure 13.

This plate 46 cooperates with a hook 44 pivotally mounted at 45 on the plate 38, for holding the auxiliary portion F in a position with its plane perpendicular to the plane of the main portion E as shown in Figure 17.

It will be understood that the auxiliary portion F may be swung into various positions with respect to the main portion E by rotation of the bar 40 upon the trunnions 39, and the auxiliary portion is shown substantially parallel to the main portion in Figure 16 so that the hanger may be conveniently packed.

While I have shown and described the invention as embodied in several different forms and with various details of construction, it should be understood that this is primarily 95 for the purpose of illustrating the principles of the invention and that many modifications and changes may be made in the details of construction without departing from the spirit or scope of the invention. For example, 100 certain details of construction in certain of the forms illustrated may also be combined with other details of construction of other forms, the various combinations of details being intended merely to illustrate the possibilities of use thereof.

Having thus described my invention, what I claim is:

1. A garment hanger comprising a main portion, including a suspending means and parts extending in opposite directions at opposite sides of said suspending means and in a common vertical plane when the hanger is suspended, said parts being shaped to receive the shoulders of a coat or the like, an auxiliary 115 trousers-supporting portion pivotally connected to said main portion, so that said auxiliary portion can be arranged selectively in positions with its plane substantially perpendicular to or substantially parallel with the 120 plane of said main portion, and means for holding said auxiliary portion in at least one of said positions.

2. A garment hanger comprising a main portion, including suspending means and parts extending in opposite directions at opposite sides of said suspending means and in a common vertical plane when the hanger is suspended, said parts being shaped to receive the shoulders of a coat or the like, the ends 130

of said shoulder-receiving parts being connected by a tie-bar, an auxiliary trousers-supporting portion pivotally connected to said tie-bar so that said auxiliary portion may be 5 arranged in positions with its plane perpendicular to or approximately parallel with the plane of said main portion, and cooperating means on said tie-bar and said auxiliary portion for holding the latter in at least one 10 of said positions.

3. A garment hanger comprising a main portion including suspending means and parts extending in opposite directions at opposite sides of said suspending means and 15 in a common vertical plane when the hanger is suspended, said parts being shaped to receive the shoulders of a coat or the like, the ends of said shoulder-receiving parts being connected by a tie-bar, an auxiliary trousers- 20 supporting portion pivotally connected to said tie-bar so that said auxiliary portion may be arranged in positions with its plane perpendicular to or approximately parallel with the plane of said main portion, said tie- 25 bar and said auxiliary portion having cooperating projections and recesses for holding the latter in either of said positions.

4. A garment hanger comprising a main portion including suspending means and 30 parts extending in opposite directions at opposite sides of said suspending means and in a common vertical plane when the hanger is suspended, said parts being shaped to receive the shoulders of a coat or the like, the 35 ends of said shoulder-receiving parts being connected by a tie-bar, an auxiliary trousers- supporting portion having a sleeve rotatably mounted on said tie-bar so that said auxiliary portion may be arranged in positions with 40 its plane perpendicular to or approximately parallel with the plane of said main portion, said tie-bar and said sleeve having cooperating projections and recesses for holding said auxiliary portion in either of said positions.

45 5. A garment hanger comprising a main portion including suspending means and parts extending in opposite directions at opposite sides of said suspending means and in a common vertical plane when the hanger is suspended, said parts being shaped to receive the shoulders of a coat or the like, the ends of said shoulder-receiving parts being connected by a tie-bar, an auxiliary trousers- 50 supporting portion pivotally connected to said tie-bar so that said auxiliary portion may be arranged in positions with its plane perpendicular to or approximately parallel with the plane of said main portion, and a hook pivotally mounted on said main portion 55 to separably engage said auxiliary portion to hold the latter in a position perpendicular to the plane of said main portion.

6. A garment hanger comprising a main portion including suspending means and 65 parts extending in opposite directions at op-

posite sides of said suspending means and in a common vertical plane when the hanger is suspended, said parts being shaped to receive the shoulders of a coat or the like, an auxiliary portion having a bar pivotally connected between the ends of said shoulder-receiving parts so that said auxiliary portion can be arranged selectively in positions with its plane substantially perpendicular to or substantially parallel with the plane of said main portion, and means for holding said auxiliary portion in at least one of said positions. 70 75

7. A garment hanger comprising a main portion including suspending means and parts extending in opposite directions at opposite sides of said suspending means and in a common vertical plane when the hanger is suspended, said parts being shaped to receive the shoulders of a coat or the like, an auxiliary portion having a bar pivotally connected between the ends of said shoulder-receiving parts so that said auxiliary portion can be arranged in positions with its plane substantially perpendicular to or substantially parallel with the plane of said main portion, and a hook on said main portion to engage said auxiliary portion for holding the latter in the first-mentioned position. 80 85 90

8. A garment hanger comprising a pair of metal strips disposed in a common plane, means for separably connecting one end of each of said strips to one end of the other, said strips being shaped to receive the shoulders of a coat or the like and the other ends of said strips being returned inwardly toward each other and each provided with an opening in alignment with the opening in the other strip, and a tie-bar having its ends 95 100 105 separably fitted in said openings.
